UNITED STATES PATENT OFFICE.

EUGEN LANGEN, OF COLOGNE, GERMANY.

OVERHEAD RAILWAY WITH SUSPENDED VEHICLES.

SPECIFICATION forming part of Letters Patent No. 546,928, dated September 24, 1895.

Application filed July 16, 1894. Serial No. 517,719. (No model.)

To all whom it may concern:

Be it known that I, EUGEN LANGEN, a citizen of Prussia, residing at Cologne, in the Empire of Germany, have invented a new and useful Overhead Railway with Suspended Vehicles, of which the following is a specification.

This invention relates to a construction of overhead railway with suspended vehicles suitable for carrying the local traffic of towns, as the loftily-situated girders, preferably of lattice construction, for carrying the track only obstruct the light and air to a slight extent, while the vehicles are so arranged that the curves of the line can readily follow the direction of all streets. In addition, the suspended arrangement of the vehicles permits of so easy and secure a motion as it is impossible to attain with vehicles running on underneath supports. The vehicles are suspended by means of swiveling-bolts at each end from rigid overhead frames carried by the running-wheels running on the overhead rails. By this means long carriages are enabled to pass over curves of very short radius, and any vertical oscillations of the carriages are prevented.

The accompanying drawings show the construction of one of the swiveling-frames. Figure 1 shows an end view of the same with cross-section of the girders and rails. Fig 2 shows a side view. Fig. 3 shows a longitudinal section. Fig. 4 shows a section on the line X X, Fig. 3; and Fig. 5 shows a section on the line Y Y, Fig. 3.

The frame A consists of two side cheeks suitably connected at top and bottom by transverse pieces A' and A'' and carried by two axles B with the running-wheels a a. The width between the rails C can be made so great in proportion to the width of the carriage that no canting over of the latter can occur from unequal loading.

In order to render the swivel-frames A entirely independent of the body of the vehicle when running on curves, the motor-engines are directly carried by the said frames.

In the present case the motors are assumed to be electromotors of any suitable construction; but other motors, such as petroleum-motors, can also be employed in a similar manner. The motor is preferably arranged be-

tween the two running-axles B, the shaft *i* thereof being parallel with these, the motion being transmitted by means of toothed wheels. 55

The motors might of course be placed in a different position and may either have their shaft connected directly with or formed in one with the axles, or the motion may be transmitted by means of worm and worm-wheel 60 gear or by belts, cords, or pitch-chains.

For preventing the running-wheels *a* from leaving the rails C there are provided safety-rollers *b*, situated immediately beneath flanges D', projecting from the bottom members of the 65 lattice-girders D, but arranged so as not to touch the flange when the vehicle is running smoothly and only coming in contact when there is excessive vertical motion.

The bottom members of the girders carrying 70 the rails C project down between the safety-rollers *b*, so that these also serve to prevent undue lateral displacement of the frame and running-wheels, such as might cause the latter to run off the rails. 75

Should the rollers *b* become fractured, excessive lateral motion will still be prevented by the upward-projecting parts *d* of the frame, which would come in contact with the sides of the bearer. Furthermore, for preventing 80 accidents on the breaking of an axle there are provided at the bottom of the frame A safety-catches *c*, which, on the frame dropping slightly on the occurrence of such a fracture, will come in contact with and rest upon 85 the rails, so as to support the vehicle.

The body E of the vehicle is suspended from the frames A by means of swivel-bolts *e*, which have their upper ends suitably carried in a swivel-bearing in the transverse part A' 90 of the frame, while the lower ends are supported in a swivel-bearing in a cross-beam F, from the ends of which the carriage-body E is suspended by bolts *g* with spring-bearings *g'*. The cross-beam F has rollers *k*, which 95 run upon curved surfaces *l*, concentric to *e* on the under side of the frame A A' when the vehicle turns on its swivel when running over curves. Safety-pins *f* are also provided on the beam F, the necks of which are situated in 100 curved slots in the bottom A' of the frame, so that should the swivel-bolt *e* become fractured the vehicle will still be supported by the collars of the pins *f* taking a bearing in

the slots. Lastly, the body E is provided with safety-straps h, passing over the ends of the beam F, so that should one of the bolts g become fractured the body will still be supported by the strap h.

5 The girders D, which may either be of lattice construction, as shown, or solid, may be supported either by brackets from lateral standards or by transverse bearers supported 10 on each side by vertical or inclined standards.

G is the electrical conductor, from which the current for the electromotor is taken by a spring conducting-lever II, carried by the frame A.

15 Having thus described the nature of this invention and the best means I know of carrying the same into practical effect, I claim—

1. In an overhead railway with suspended vehicles, the combination of a truck frame A 20 supported by wheels a on the rails, and having a laterally extended lower part A³ carrying safety rollers b adapted to bear against the under side of the main girders D of the line, a transverse bearer F, from which the 25 car body is suspended by bolts g and springs g', and which is itself suspended from the part A³ of the truck frame by a swiveling suspension bolt e, and rollers k on bearer F bearing against the under side of said part A³, 30 so as, with the bolt e to constitute a turntable for facilitating the turning of the frame A A³ relatively to the bearer F and car body, substantially as described.

2. In an overhead railway with suspended vehicles, the combination of a truck frame A 35 supported by wheels a on the rails, and composed of side frames connected by transverse pieces A' A² A³, of which A² carries safety supports c, adapted to come in contact with 40 the rails, while A³ carries safety rollers adapted to bear against the under side of the girders D, a swiveling bolt e suspended from the part A³ of the truck frame and serving as means of suspension for a transverse bearer 45 F, from which the car body is hung and roll-

ers k carried by said bearer F and adapted to bear against the under side of part A³ of the frame, substantially as described.

3. In an overhead railway with suspended vehicles the combination of a truck frame A 50 supported by wheels a and carrying safety supports c a transverse bearer F from which the body of the vehicle is suspended, a swiveling bolt e connecting frame A with bearer F, safety rollers b carried by frame A adapted 55 to bear against the under side of girders D of the line, rollers k on bearers F bearing against the under side of frame A, and projecting parts d on frame A projecting up beyond parts of the bottom members of the 60 girders D for preventing excessive lateral motion of the frame, substantially as described.

4. In an overhead railway with suspended vehicles, the combination of the transverse 65 bearers F, bolts g with springs g' connecting the bearers with the body of the vehicle E and safety looped straps h fixed to the body E and extending over the bearer F for supporting the body E in the event of one or 70 more of the bolts g or springs g' breaking, substantially as described.

5. In an overhead railway with suspended vehicles, the combination of the truck frame A, transverse bearer F supporting the carriage body E, swivel bolt e connecting bearer F with truck frame A, and pins f passing through curved slots in the bottom plate of the frame A, said pins having enlarged heads 75 above the slots so as to support the vehicle in 80 the event of the swivel bolt fracturing, substantially as described.

In testimony whereof I have signed my name to this specification, in the presence of two subscribing witnesses, this 30th day of 85 June, A. D. 1894.

EUGEN LANGEN.
